(57) **CLAIM**

The ornamental design for a video conference system endpoint, as shown and described.

DESCRIPTION

FIG. 1 is a front perspective view of the video conference system endpoint;

FIG. 2 is a rear perspective view of the video conference system endpoint;

FIG. 3 is a front elevation view of the video conference system endpoint;

FIG. 4 is a rear elevation view of the video conference system endpoint;

FIG. 5 is a side elevation view of the video conference system endpoint; and

FIG. 6 is a side elevation view of the video conference system endpoint.

FIG. 7 is a top perspective view of the video conference system endpoint;

FIG. 8 is a bottom perspective view of the video conference system endpoint;

FIG. 9 is a top plan view of the video conference system endpoint; and,

FIG. 10 is a bottom plan view of the video conference system endpoint.

Any portions shown using dashed lines are for illustrative purposes only and form no part of the claimed design.
